INVENTOR:
Isaac Brooke,
BY *John A. Diederichs*,
ATTORNEY.

UNITED STATES PATENT OFFICE.

ISAAC BROOKE, OF ROYER'S FORD, PENNSYLVANIA.

INKSTAND.

SPECIFICATION forming part of Letters Patent No. 280,568, dated July 3, 1883.

Application filed June 17, 1882. (No model.)

To all whom it may concern:

Be it known that I, ISAAC BROOKE, a citizen of the United States, residing at Royer's Ford, in the county of Montgomery, State of Pennsylvania, have invented a new and useful Improvement in Inkstands, which improvement is fully set forth in the following specification and accompanying drawings, in which—

Figure 1 is a top or plan view of the inkstand embodying my invention. Fig. 2 is a vertical section on line *x x*, Fig. 1. Fig. 3 is a vertical section on line *y y*, Fig. 2.

Similar letters of reference indicate corresponding parts in the several figures.

15 My invention consists in an inkstand having a sliding cover, which is opened by a lever, to which motion is imparted by the pressure or weight of the hand, the cover being closed when said lever is relieved of the hand.

20 Referring to the drawings, A represents a base, on which is supported the ink well or holder B, having a cover, B'. Rising from the base A, on opposite sides of the ink-well, are lugs A', which form the bearings for a forked lever, C, whose front end, *a*, constitutes a rest, on which the hand of the writer is to be placed for opening the cover B', as will be hereinafter set forth.

25 D represents an elbow-lever, which is mounted on the base A opposite to the resting end *a* of the lever C, and pivoted to the adjacent end of the cover B', the lower end of the lever D being in contact with or pivoted to the connecting-bar *b* of the forked portions of the lever, a spring, D', being connected with the lever D and base A for restoring said lever D and, consequently, the cover B' to their normal positions, and closing the ink-well.

30 E represents upright pieces, which rise from the base A on opposite sides of the ink-well, and have at their lower ends curved lips *d*, which enter openings in the base A. A cross bar or binder, F, which is vertically slotted or forked, is fitted to said side pieces, E, and has in its bottom an opening, *e*, below the base for the reception of a pin, key, or wedge, G, whereby the binder is firmly secured to the base and the side pieces are rigidly held in upright position. The side pieces are scalloped to form 35 a rack or holder for pens, &c.

40 The top collar or flange, *e'*, of the ink-well is circumscribed by a fixed collar, H, which

is formed with an extension, H', projecting toward the binder F, the upper face of the extension being grooved, as at *f*, to receive a 55 teat or stud, *g*, which depends from the other side of the cover B' of the ink-well. A portion of the collar H, corresponding to the front of the ink-well, is raised, and its inner face is grooved to receive the edge of the cover B', it 60 being seen that said cover has a sliding motion on the lower portion of the collar H, and is guided by the teat *g* in the groove *f* and the grooved sides of the collar H, it also being seen that the extension H' of said collar has its outer 65 end sustained on the binder F, and the cover B' is partly supported on said extension.

65 The operation is as follows: When ink is required, a hand or one or more fingers are placed or pressed on the rest *a* of the lever C, 70 thus lowering the outer end of the lever and raising the cross-bar *b* at the inner end thereof. This operates the elbow-lever D, the upper end whereof moves outwardly or from the ink-well, and carries with it the cover B', thus 75 opening the ink-well and permitting the pen to be dipped therein. When the hand is removed from the rest A, the parts quickly return to their normal position, and the ink-well is again closed, this being accomplished 80 by the action of the spring D', which exerts its pressure on the elbow-lever D, the latter being in contact with the cross-bar *b*, and pressing against the same; but if the lever D is connected with the cross-bar *b*, the latter may be 85 weighted and accomplish the same result as the spring D'. As the lever C is loosely fitted on the bearing-lugs A', its displacement is prevented by studs J, which project inwardly from the sides of the upright pieces E above 90 the lever, without, however, interfering with the freedom of pivotal motions of said lever. When the cover B' is in its normal position, it closes the ink-well with a tight joint, owing to the groove of the collar H receiving the edge 95 of the cover.

I am aware that it is not new to provide an inkstand with a pivoted cover which is raised by the action of a lever when a hand is placed thereon; but, as by my sliding cover I avoid 100 the noise occasioned by the return of the pivoted cover as it strikes the ink-well, I have made an improvement in the art; wherefore,

Having fully described my invention and

the advantages thereof, what I claim as new, and desire to secure by Letters Patent, is—

1. In an inkstand, a sliding cover, in combination with a hand-resting lever and a 5 connecting-lever, substantially as described, whereby said hand-resting lever is adapted to operate said sliding cover.

2. The ink-well base, hand-resting lever, elbow-lever, and spring, in combination with 10 the sliding cover, substantially as and for the purpose set forth.

3. In an inkstand, a sliding cover provided 15 with a stud, *g*, the ink-well having a collar which is provided with a grooved extension, *H'*, the lever *D*, and the hand-resting lever *C*,

combined and operating substantially as and for the purpose set forth.

4. The sliding cover and ink-well, in combination with the collar *H* and the binder *F*, said collar having an extension, *H'*, which 20 rests on said binder and guides and supports the sliding cover, substantially as and for the purpose set forth.

The above specification of my invention signed by me.

ISAAC BROOKE.

In presence of—

JOHN A. WIEDERSHEIM,
A. P. GRANT.
